(57) **CLAIM**

The ornamental design for a shaver, as shown and described.

DESCRIPTION

FIG. 1 is a front, top, right perspective view of a first embodiment of a shaver showing the new design in a state of use;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a front, top, right perspective view of a second embodiment of a shaver showing the new design in a state of use;

FIG. 8 is a front elevation view thereof;

FIG. 9 is a rear elevation view thereof;

FIG. 10 is a left side view thereof;

FIG. 11 is a right side view thereof;

FIG. 12 is a top plan view thereof;

FIG. 13 is a front, top, right perspective view of a third embodiment of a shaver showing the new design in a state of use;

FIG. 14 is a front elevation view thereof;

FIG. 15 is a rear elevation view thereof;

FIG. 16 is a left side view thereof;

FIG. 17 is a right side view thereof; and,

FIG. 18 is a top plan view thereof.

The dark shading surrounding the shaver head and the lighter shading on the shaver head indicate illumination when the shaver is in a state of use.

1 Claim, 18 Drawing Sheets
